UNITED STATES PATENT OFFICE.

FRANK HEDLEY, OF YONKERS, AND JAMES S. DOYLE, OF MOUNT VERNON, NEW YORK.

MECHANICALLY-OPERATED MULTIPLE-UNIT DOOR-CONTROL SYSTEM FOR CARS.

Application filed July 25, 1919. Serial No. 313,405.

To all whom it may concern:

Be it known that we, FRANK HEDLEY and JAMES S. DOYLE, both citizens of the United States, and residents, respectively, of Yonkers and Mount Vernon, in the county of Westchester, State of New York, have invented a new and useful Improvement in Mechanically-Operated Multiple-Unit Door-Control Systems for Cars, of which the following is a specification.

This invention relates to mechanically operated multiple unit car door control systems.

The object of the invention is to provide a multiple unit door control system which is simple, efficient, economical to manufacture, install or maintain, and wherein the desired control of the doors of cars is effected mechanically.

20 A further object of the invention is to provide a door control system of the nature referred to wherein the proper operation of all the doors on the same side of adjacent cars of a train is accomplished mechanically from the same station and by a single operator.

25 A further object is to provide a door control system of the nature referred to wherein the doors are motor operated in their opening and closing movements, and wherein the operating motors for the doors on each side of the car are all mechanically controlled from the same point or station at either end of the car.

30 Other objects of the invention will appear more fully hereinafter.

The invention consists substantially in the construction, combination, location and relative arrangement of parts, all as will be 40 more fully hereinafter set forth, as shown by the accompanying drawings, and finally pointed out in the appended claim.

In the drawings,—

45 Fig. 1 is a view in side elevation of one car and a portion of the adjacent end of another car in a train of cars showing the application thereto of a mechanically operated multiple unit door control system embodying the principles of our invention.

50 Fig. 2 is a broken view in side elevation of one end of a car showing the mechanically operated control devices.

Fig. 3 is an end view of the car.

55 Fig. 4 is a broken view in perspective showing a structure of mechanical devices

and connections suitable for use in carrying out our invention.

Fig. 5 is a broken view in vertical section transversely of the car showing a door operating motor and mechanical control connections therefor in accordance with the principles of our invention.

The same part is designated by the same reference numeral wherever it occurs throughout the several views.

Heretofore it has been a common practice in the operation of subway and elevated car systems to employ a plurality of cars connected up into a train of cars, and under the modern requirements of rapid transit it is not unusual to couple up as many as ten cars into a single train. It is also a common practice to employ three or more doors on each side of each car, one door on each side being located at or adjacent each end of the car, and one located intermediate the car ends. It is also a common practice to employ power motors to effect the opening and closing movements of the doors. Usually a separate motor is employed for each door.

According to this practice it is the universal custom to employ a guard at each end of each car, that is, a guard between the proximate ends of each pair of cars, each guard controlling the operation of the end doors of the adjacent car ends where he is stationed, and also the center or intermediate door on one of the cars. This practice necessitates the employment of at least nine guards, besides the motorman, on a ten car train, thereby imposing a heavy financial burden upon the management of the system to meet the wage requirements of train crews of this size. Since rapid transit requirements demand the operation of trains with comparatively short intervals of time between succeeding trains, it will be readily understood that the wage requirements amount to extremely large proportions for the operation of trains in a system like the subway system of New York city, for example. With the increased costs of material, fuel, labor, and other items required in the operation of a street, elevated, or subway system, the operating companies have found it extremely difficult to meet the operating expenses from the low fares demanded by the public, and consequently the problem of reducing the expenses without decreasing the efficiency of the system, or the safety

of operation, is one towards which attention of the engineers is being concentrated. It is proposed, according to our present invention, to attain the result sought by very largely reducing the number of guards required to operate or control the doors on a train of cars. For example, where it has heretofore been necessary to employ at least nine guards for a ten car train, we provide 10 a door control mechanism which will permit dispensing with the services of at least four of the nine guards for each ten car train, and we propose to accomplish this result without sacrificing anything of efficiency or 15 safety of operation of the system. On the contrary the safety of operation of trains is increased in the use of a control system embodying our invention.

One important factor enters into the problem, namely, the expense of equipping cars or trains with new appliances and devices, and the time required, under existing labor and manufacturing conditions, to equip the cars of a street or other railway system with 20 such new appliances and devices. Obviously, if such cost of new equipment approximates in amount the wages of the guards whose services are to be dispensed with then no relief is secured from the financial burdens of the company. It is therefore among the special purposes of our present invention to provide mechanically operated devices and connections to control the door actuating motors, of such nature 25 and relation as will permit largely the use of present equipment of the cars, and require the use of but few simple, inexpensive additional parts which can be readily, easily and quickly installed on the present 30 rolling stock, and this characteristic of our invention we regard as of prime importance and value as it enables street and other railway companies to secure the benefits and advantages of our invention without delay 35 or excessive or prohibitive expense, indeed, at very slight expense and by utilizing the present rolling stock with its present equipment.

Referring to the drawings, reference numerals 6, 7, designate respectively the proximate ends of adjacent cars of a train. Each car is provided with the usual end doors 8, 9, and the intermediate door 10, in each side thereof. Each door is operated by a motor 11 in the usual manner. A rock shaft 12 is suitably supported beneath the body of the car at each side thereof, the said shafts extending the whole length of the car. The shaft 12 carries a crank arm 13, at each end thereof beneath the floor of the car end vestibule. Each crank arm 13 is connected by means of a rod 14, to an operating lever 15, which is pivotally mounted as at 16 upon the outer end wall surface of the car end. 60 Each operating lever 15 is preferably,

though not necessarily, formed or connected with a segment gear 17, see Fig. 4, which meshes with a pinion 18, to which is connected a counterweight 19.

This arrangement facilitates and renders 70 quite easy the operation of rocking the shafts 12 from their operating levers 15 at either end of the car.

Each shaft 12 is also provided with a crank arm 20 at or adjacent each door operating motor on the same side of the car. Each crank arm 20 is suitably connected to an arm 21 through which the operation of the associated motor is controlled. For example, the arm 21 may be the motor control 75 valve operating arm.

From the foregoing description it will be seen that when any one of the levers 15 at either end or side of a car is rocked, the shaft 12 on the corresponding side of the car is coincidentally rocked, this manipulation being accomplished easily and smoothly by reason of the counterweight arrangement above described. The rocking of a shaft 12 on either side of the car simultaneously operates the control connections for each door actuating motor, on the same side of the car therewith, thereby simultaneously moving all the doors on that side of the car. Since each car of the train is similarly equipped it 85 will be seen that a single guard stationed between the proximate ends of two adjacent cars of a train is enabled to manipulate the control lever 15 on the same side of each of the cars, which manipulation may be effected simultaneously or selectively, thereby causing all the doors on the same side of both or either car at will to be simultaneously opened or closed.

To facilitate the work of the guard and to enable him to observe the boarding and alighting movements of passengers at or in the vicinity of the doors under his control, a raised lookout platform 22 is positioned on the exterior wall of each car end below each 90 motor control lever 15, a sufficient distance for a guard to stand thereon while manipulating the control levers, thereby occupying an elevated position and enabling him to see over the heads of passengers.

The gears 17, 18, and weight 19 are preferably enclosed within a shield or casing 23, which may afford a convenient arm rest for the guard when occupying his lookout or observation position on the platform 22.

If desired, and in order to still further insure safety of operation, a telltale or indicator device 24, may be associated with each door to indicate whether or not it is open or closed.

From the foregoing description it will be seen that we provide an exceedingly simple and efficient mechanical control for the doors in a multiple unit car door control system which is economical to install and maintain,

and wherein only one guard or operator is required for all the doors on each pair of cars in a train. Moreover, since it is the present custom to employ operating levers 5 for the end gates on elevated railway cars, and for the end doors of subway cars, it requires but very little additional connections or devices to apply a mechanical door control construction embodying our invention 10 to the present rolling stock equipment, and hence the conversion of the present equipment may be effected expeditiously and at small expense.

It is to be understood that variations and 15 changes in details will readily occur to those skilled in the art without departure from the spirit and scope of our invention.

Having now set forth the objects and nature of our invention, and a construction embodying the principles thereof, what we 20 claim as new and useful and of our joint in-

vention, and desire to secure by Letters Patent is—

In a mechanically operated multiple unit car door control system, and in combination 25 with the cars of a train, and a plurality of sliding doors for each car, of a rock shaft extending longitudinally the length of each car, means adjacent the doors for sliding said doors to and fro, crank arms on said shaft in operative connection with said door sliding means, a rocker arm fastened to the end of said rocker shaft, said arm pivotally carrying an operating lever, and a 30 governor for said lever for smoothly operating said lever and rocker shaft.

In testimony whereof we have hereunto set our hands on this 22d day of July, A. D., 1919.

FRANK HEDLEY.
JAMES S. DOYLE.
